DESIGN FOR A MECHANICAL PENCIL

Maurice J. Waldinger, Flushing, N. Y.

Application November 25, 1944, Serial No. 116,560

Term of patent 14 years

(Cl. D74—24)

To all whom it may concern:

Be it known that I, Maurice J. Waldinger, a citizen of the United States of America, residing at 170-13 35th Avenue, Flushing, Long Island, in the county of Queens and State of New York, and whose post office address is 45 East 20th Street, New York 3, N. Y., have invented a new, original, and ornamental Design for a Mechanical Pencil, of which the following is a specification, reference being had to the accompanying drawing, forming part thereof.

Figure 1 is a side elevational view of a mechanical pencil showing my new design without the clip; and

Figure 2 is a side elevational view thereof, with a clip attached thereto.

I claim:

The ornamental design for a mechanical pencil, substantially as shown.

MAURICE J. WALDINGER.
